UNITED STATES PATENT OFFICE.

EDWARD T. RICHARDS, OF CHICAGO, ILLINOIS.

DESIGN FOR A STATUETTE.

40,621.

Specification for Design. Patented Apr. 12, 1910.

Application filed November 4, 1909. Serial No. 526,311. Term of patent 7 years.

To all whom it may concern:

Be it known that I, EDWARD T. RICHARDS, a citizen of the United States, residing at Chicago, in the county of Cook and State of Illinois, have invented a new, original, and ornamental Design for a Statuette, of which the following is a specification, reference being had to the accompanying drawing, forming a part thereof.

The figure is a front elevation of a statuette, showing my new design.

I claim:

The ornamental design of a statuette as shown.

ED. T. RICHARDS.
